CONDENSER SYSTEM FOR RAILWAY CARS

John G. Bergdoll, York, Pa., assignor to York
Ice Machinery Corporation, York, Pa., a cor-
poration of Delaware

Application March 6, 1935, Serial No. 9,680

6 Claims. (Cl. 257—25)

This invention relates to refrigeration and particularly to refrigeration as applied to railway cars, the important features of novelty residing in the means used to condense the refrigerant. 5 The invention has been developed particularly with reference to conditioning air in passenger cars and certain problems inherent in such installations will be discussed, but broadly considered, the invention is applicable to refrigeration 10 systems used on cars and other vehicles, regardless of the purpose to which the refrigeration is applied.

Refrigerative conditioning plants as applied to railway cars are in operation only when atmospheric temperatures are relatively high. There is no location on the exterior of the car at which condenser cooling air at low temperature is available, and as a practical matter location of the condenser beneath the car body is virtually necessary. 15 In such a location the condenser is subject to heat radiated from the road bed, and in the path of air which has derived heat from the locomotive or other propelling units.

The use of air cooled condensers is desirable 20 because it is impracticable to carry in the car sufficient water for water cooling unless cooling towers are used. Space for cooling towers is not conveniently available, and even if available the wide ranges of temperature encountered on long trips, and the conditions developed by entrance 25 of cinders and dirt, introduce serious maintenance problems. This has been demonstrated in actual experience with railway car installations using cooling towers.

It has heretofore been proposed to increase the efficiency and reduce the head pressure of air 30 cooled condensers by humidifying, substantially to the point of saturation, the cooling air passed over the condenser. It has also been proposed 35 to subdivide an air cooled condenser and humidify the air heated by one subdivision before passing such air into heat exchanging relation with another subdivision.

The present invention resides in the application 40 of such a condensing system to railway cars. Important features of novelty are the delivery of humidifying water by pressure derived from the air brake system, and control of water delivery by head pressure (in the condenser) or equivalent means, so that water will be used only 45 when conditions are such as to require it. As refinements of the invention means are shown to assist the air flow over the condenser by the motion of the car. As the direction of motion 50 of railway cars is frequently reversed, it is nec-

essary, where air circulating fans are used, to reverse the fans in response to reversal of motion of the car, and in some cases also to deliver the water selectively to different humidifying nozzles. Such arrangements will be described 5 as embodied in modifications.

In the drawings:—

Fig. 1 is a side elevation of a passenger car with the invention applied, showing the preferred location of the condensers and water storage 10 tank.

Fig. 2 is a perspective view showing the brake pipe, water storage system and refrigeration circuit.

Fig. 3 is an elevation of one of the condenser 15 units, as viewed in Fig. 1.

Fig. 4 is a section on the line 4—4 of Fig. 3.

Fig. 5 is a section similar to Fig. 4 showing a modification of the condenser.

Fig. 6 is a similar view of another modification. 20

Fig. 7 is a detail view of a device used with the structure of Fig. 6 to select the nozzles.

The embodiment shown in Figs. 1 to 4 will first be described.

A passenger car body of conventional form is 25 illustrated at 11 and is supported on trucks 12 (Fig. 1). Hung beneath body 11 in the interval between the trucks 12 are all the components of the refrigerating system shown in Fig. 2, except the evaporator and related components of the 30 conditioning unit. Those units which are indicated in Fig. 1 are the water storage tank 13, two condensers 14 and conditioning unit 15 (which includes the evaporator, and also related parts not concerned with the present invention 35 and hence not illustrated, such as circulating fans and the like).

Referring to Fig. 2 a multi-cylinder air cooled 40 compressor is indicated at 16. No driving means is shown and any known in the art may be used, such as mechanical drive from an axle of a truck 12, or electrical drive using current from any source such as a battery charged by an axle-driven generator, the latter being the usual commercial practice. 45

The compressor 16 discharges through line 17, 18 and branches 19 to two condensers, indicated generally by numerals 14. The use of a plural 50 ity of condensers is commonly dictated by space considerations and any suitable number, one or more, may be used as circumstances render advisable. From condensers 14 branch liquid lines 21 lead to liquid line 22 which delivers refrigerant to receiver 23, having a charging and purge connection 24 and sight glasses 25. 55

From the receiver 23 line 26 leads through strainer 27 to the expansion valve 28, which delivers refrigerant through pipe 29 to an evaporator, not illustrated in detail, but forming an essential part of the conditioning unit 15. The discharge header of the evaporator is indicated in dotted lines at 31 and is connected to the suction line 32 which leads to the suction connection 33 of the compressor 16 through a strainer 34.

Expansion valve 28 is preferably of the automatic type and may be of any suitable construction. In Fig. 2 is shown a thermostatic bulb 30 connected by tube 35 with the body of valve 28 to exercise control in response to the temperature of evaporator discharge. It is to be understood that the valve includes some control in response to evaporator pressure. No novelty is here claimed for the expansion valve.

20 A high pressure cut-out 36 connected by branch 37 with discharge line 17 is provided to shut down compressor 16 if discharge pressure rises above a safe working limit. This limit is higher than the pressure at which the automatic 25 water control valve, hereinafter described, is set to operate.

The brake pipe forming part of an air brake system is shown at 38. This may be any brake pipe under suitable air pressure. In the usual 30 automatic systems used on passenger cars, the air pressure in the brake pipe is 110 pounds gage under running conditions. Running pressures as low as 70 pounds gage are, however, used in some classes of service. Leading from brake 35 pipe 38 is a branch 39 which delivers air to a reducing valve 41, set to charge a storage reservoir 42 to a lower pressure say 60 pounds gage, and hold such charge against reflux to the brake pipe despite reductions of brake pipe pressure 40 made from time to time to produce brake applications.

A second reducing valve 43 delivers air from reservoir 42 to line 44 at a still lower pressure, say 20 pounds gage. Line 44 leads to water 45 storage tank or reservoir 13 and thus places the water under a static head of 20 pounds gage.

A dip pipe 45 delivers water through a normally open hand operated stop valve 46 and strainer 47 to a water regulating valve 48 which 50 controls the supply of water through line 49 to the spray heads of condensers 14. The valve 48 is operated by a pressure motor 51 subject to pressure in pipe 18 through branch connection 52 and is so contrived that valve 48 will open 55 and close as pressure in line 18 passes above and below a chosen value.

With one refrigerant commercially used in railway car conditioning this value has been satisfactorily set at approximately 160 pounds 60 gage, but the pressure is selected on the basis of economic head pressure limits and depends in part on the thermodynamic characteristics of the refrigerant to be condensed. The purpose of the valve is to suspend humidification and 65 conserve water when reasonable head pressures are attainable without humidification of the cooling air.

While valve 48 responds directly to head pressure, it responds indirectly to those atmospheric 70 conditions which control head pressure under operating conditions. Broadly considered therefore the opening and closing movements of valve 48 are controlled by the physical condition of cooling air approaching the condensing unit or 75 units, and approximately equivalent results can

be secured by means other than a controller responsive directly to head pressure, though this last is preferred.

The construction of the condensing units 14 can be best explained with reference to Figs. 3 5 and 4. A horizontal duct or housing made up of top plate 53, bottom plate 54 and side plates 55 is closed at one end by a grille or screen 56 and at the other end by a plate 57 having two circular apertures, in each of which is mounted 10 a two-bladed air-circulating fan 58 driven by a corresponding electric motor 59. The air enters through the screen and is drawn through the duct by the fans which operate whenever compressor 16 is running. 15

The branches 19 deliver compressed refrigerant to a top header 61 in each condenser and the condensed refrigerant is collected by bottom headers 62, one in each condenser and delivered to the branches 21 of the liquid line. Connected 20 to and extending between headers 61 and 62 are coils arranged in two groups spaced a short distance apart in the direction of air flow. The first group comprises a small number of coils 63 and the second group a larger number of coils 64. 25

Between the two groups and directed toward the first are atomizing nozzles 65 fed by supporting stand pipes 66 which are connected to branches of water pipe 49. A nozzle is shown in front of each fan 59, so that they discharge 30 substantially at the center of the air stream induced by each fan.

The capacity of the water nozzles 65 is small, only about two gallons per hour for each nozzle being required in a four nozzle installation as 35 commercially used on a standard railway car. Air heated by coils 63 is cooled and humidified by the atomized water before contact with the coils 64. Neither set of coils is wet to any material extent as the spray evaporates almost entirely 40 in suspension in the air. The beneficial effect of this comparatively insignificant quantity of water, used as described, is surprisingly great. In commercial installation on railway cars as 45 mentioned above using "Freon" as a refrigerant, the effect under actual service conditions is to reduce head pressure in the condenser from about 200 pounds to 160 pounds gage. The saving in power consumption, and the reduced wear on the compressor, are of peculiar importance 50 in this class of service.

Since the coils are not drenched and since no water is recirculated, the difficulties encountered with cooling towers, because of scaling of coils and clogging of water connections by cinders and dust, are avoided. It is a simple matter to 55 drain the spray system as an incident to shutting it down, so that freezing up in cold weather does not occur.

In the embodiment above described the air 60 entrance to the condensers 14 is at the side of the car, so that the air flows through the condenser housing in a direction transverse to the car.

The duty on the fan motors 59 can be reduced 65 somewhat by causing the air flow to occur in harmony with the travel of the car, but in such case the fans must be reversed as an incident to reversal of direction of travel of the car, and in some installations it may be desirable to cause 70 different sets of nozzles to operate in different directions of car travel.

Figs. 5 and 6 show modifications illustrative of the principles involved.

In Fig. 5 the groups of coils 63a and 64a are 75

- similar in size and the nozzle 65a is mounted between them. The reversible direction of motion of the vehicle is indicated by a legend. The fan 58a is driven by a shaft 71 through a belt. Shaft 71 may be the car axle, or the shaft of a reversible motor whose direction of rotation is reversed preferably automatically by reversals of car travel, so that the fan assists the natural air flow.
- 10 In Fig. 6 a single group of coils 63b is used instead of two groups. Two spray nozzles 65b and 65c are used, one on either side of coil 63b and means, preferably automatic, are provided to deliver water to them selectively, so that only air approaching the coil is humidified.
- 15 The fan 58b is driven by a belt from shaft 71b which reverses as the car travels in reverse directions. As in the case of Fig. 5, shaft 71b may be a car axle or a reversible motor. Between the pulley 72b and fan 58b is a bevel planetary train made up of two sun gears 73b and 74b and a planet gear 75b mounted to swing about the common axis of gears 73b and 74b. Gear 73b is fast to pulley 72b and gear 74b fast 20 to fan 58b.
- 25 The reversal of torque as the drive reverses will cause displacement of planet gear 75b which is connected by link 76b to valve 77b in valve body 78b. (See Fig. 7.) Shifting of valve 77b connects water supply line 49b selectively to nozzles 65b and 65c, so that only the nozzle on the air entrance side is active. The planetary gearing is only diagrammatically indicated and is merely typical of valve shifting means responsive to reversal of direction.
- 30 One important aspect of Fig. 6 should be particularly observed. Air approaching the condenser is heated, by the propelling unit and also by radiation of heat from the road bed as above explained, and hence is in condition to receive and quickly evaporate moisture. Thus it is in condition to receive considerable additional humidity, and active evaporation of the spray occurs in advance of the condenser coil 63b.
- 40 45 The various embodiments above described are intended to be illustrative and not limiting.
- What is claimed is:—
1. The combination of a vehicle having a brake pipe in which pneumatic pressure is developed; a water reservoir subject to static pressure derived therefrom; a surface condenser; means for passing air in heat exchanging relation with said condenser; and means for humidifying said air prior to contact with a portion of said condenser, comprising water spraying means operated by the static head on said water.
  2. The combination of a vehicle having a brake pipe in which pneumatic pressure is developed; a water reservoir subject to static pressure derived therefrom; a surface condenser; means for passing air in heat exchanging relation with said condenser; means for humidifying said air, prior to contact with a portion of said condenser, comprising water spraying means operated by the static head on said water; and means responsive to condenser pressure and controlling the delivery of such water alternately to cause and suspend humidification as condenser pressure passes above and below a chosen value.
  3. The combination of a vehicle adapted to travel in relatively reverse directions; a source of water thereon; a condenser, in heat exchanging relation with which air is circulated in relatively reverse directions as an incident to relatively reverse travels of the car; and means controlled by the direction of motion of the car for delivering moisture from said source to air approaching at least a part of said condenser to humidify the same.
  4. The combination of a vehicle adapted to travel in relatively reverse directions; a source of water under pressure head carried by said vehicle; a surface condenser exposed to air flow induced at least in part by motion of the vehicle; a pair of spray devices, one for humidifying air passing over the condenser in each direction of motion of the vehicle; and means responsive to direction of motion of the vehicle for delivering water from said source to said spray devices selectively.
  5. The combination of a vehicle adapted to travel in relatively reverse directions; a source of water under pressure head carried by said vehicle; a surface condenser exposed to air flow induced at least in part by motion of the vehicle; and a pair of spray devices, one for humidifying air passing over the condenser in each direction of motion of the vehicle.
  6. The combination of a vehicle, including a pneumatic brake system and an air storage reservoir charged from said system; water storage means carried by said vehicle; connections for placing the water in said storage means under pressure head derived from said reservoir; a surface condenser; means for passing air in heat exchanging relation with said condenser; and means for spraying water under said pressure head into the last named air as the latter approaches at least a portion of said condenser, and at a rate which will ensure evaporation of the water in the air without substantially wetting said condenser.

JOHN G. BERGDOLL.
